UNITED STATES PATENT OFFICE.

WILLIAM MCCLINTOCK, OF NEW YORK, N. Y.

CLAMP FOR MARBLE WASH BOWLS OR BASINS.

SPECIFICATION forming part of Letters Patent No. 707,153, dated August 19, 1902.

Application filed January 2, 1902. Serial No. 88,141. (No model.)

To all whom it may concern:

Be it known that I, WILLIAM MCCLINTOCK, a citizen of the United States, residing at New York, in the county of New York and

5 State of New York, have invented certain new and useful Improvements in Clamps for Marble Wash Bowls or Basins, of which the following is a full and complete specification, such as will enable those skilled in the art to which

10 it appertains to make and use the same.

The object of this invention is to provide improved means for securing wash bowls or basins to a marble slab, whereby the bowl or basin may be more easily and conveniently 15 and safely secured to the slab than is possible with devices now employed for said purpose, a further object being to provide improved means for securing a wash bowl or basin to a marble slab without the risk of 20 breaking the basin or the slab; and with these and other objects in view the invention consists in the construction, combination, and arrangement of parts hereinafter described and claimed.

25 In the drawings forming part of this specification, in which the separate parts of my improvement are designated by the same reference characters in each of the views, Figure 1 is a transverse section of a marble slab 30 or table and showing a wash bowl or basin secured thereto by means of my improved clamp, and Fig. 2 a bottom plan view thereof.

In the drawings forming part of this specification I have shown at *a* an ordinary 35 marble slab or table provided with the usual opening *a*² and below which is secured a bowl or basin *b*. The bowl or basin *b* is provided at the top with an annular flange or rim *b*², all these parts being of the usual construction, and in the practice of my invention I provide an angular clamp-piece *c*, comprising 40 a horizontal portion *c*², adapted to fit flush with the bottom of the slab or table *a*, an angular central portion *c*³, and a horizontal bottom portion *c*⁴, adapted to fit beneath the flange or rim *b*² of the bowl or basin *b*. The part *c*² of the clamp *c* is provided with a longitudinal slot *c*⁵, and in practice I provide a clamp bolt or member comprising a shank *d*, 45 adapted to be secured in the slab or table *a*, and a head portion *d*², formed at a slight angle thereto and through which is passed a set-

screw *e*, which is adapted to bear on the angular portion *c*³ of the clamp and to force the same against the flange or rim *b*² of the bowl 55 or basin *b*.

The shank *d* of the clamp bolt or member is passed through the slot *c*⁵ and sunk into the hole bored in the bottom of the slab or table *a*, as shown at *a*³, and this hole is inclined outwardly, so as to more securely hold the clamp bolt or member, and said clamp bolt or member may be secured in said hole in any desired manner. In practice I prefer to make said hole *a*³ of about the same diameter as the shank of the clamp bolt or member, and when thus constructed the clamping action of the screw *e* will also serve to hold said clamp bolt or member in the slab or table *a*; but by coating the said shank of 60 the clamp bolt or member with liquid cement and then inserting the same into the hole *a*³ the said clamp bolt or member will remain secure in the slab or table *a* under all circumstances.

In Fig. 2 of the drawings I have indicated 75 the use of four of these devices for securing the bowl or basin in place, three thereof being shown and one side of the bowl or basin being broken away, but any desired number 80 of which may be employed, and three will be found sufficient under most circumstances.

My improved device for securing a bowl or basin to a slab or table is simple in construction and easy of connection, and by means 85 thereof a bowl or basin may be secured in place without danger of breaking the same, and the fastening devices will remain securely connected with the slab or table.

The clamps *c* may be turned on the clamp 90 bolt or member by releasing the set-screw *e*, and by this means a new bowl may be quickly and easily substituted for an old one whenever desired.

Having thus fully described my invention, 95 what I claim as new, and desire to secure by Letters Patent, is—

1. The herein-described means for securing a bowl or basin to a marble slab or table comprising an angular clamp-piece, the ends 100 of which are parallel and project in opposite directions and the central portion of which is at an angle to said ends, one of said ends being provided with a slot or opening, and a

clamp bolt or member passed therethrough and adapted to be secured in the marble slab or table, said clamp bolt or member being provided in the outer end thereof with a set-screw which is passed therethrough and adapted to bear on the angular portion of the clamp, substantially as shown and described.

2. The herein-described means for securing a bowl or basin to a marble slab or table comprising a clamp c provided with parallel end portions c^2 and c^4 which project in opposite directions and which are connected by an angular portion c^3 , the end portion c^2 being provided with a slot or opening c^5 , and a

clamp bolt or member passed therethrough 15 and secured in the slab or table, the outer end of said clamp bolt or member being provided with a set-screw e , substantially as shown and described.

In testimony that I claim the foregoing as 20 my invention I have signed my name, in presence of the subscribing witnesses, this 28th day of December, 1901.

WILLIAM McCLINTOCK.
